INVENTOR
Joseph P. Baumgartner
BY
Alfred Diederichs,

ATTORNEY.

UNITED STATES PATENT OFFICE.

JOSEPH P. BAUMGARTNER, OF PHILADELPHIA, PENNSYLVANIA.

BUNG.

SPECIFICATION forming part of Letters Patent No. 614,603, dated November 22, 1898.

Application filed August 29, 1896. Serial No. 604,251. (No model.)

To all whom it may concern:

Be it known that I, JOSEPH P. BAUMGARTNER, a citizen of the United States, residing in the city and county of Philadelphia, State of Pennsylvania, have invented a new and useful Improvement in Bungs, which improvement is fully set forth in the following specification and accompanying drawings.

My invention consists of an improved construction of bung in which provision is made for expanding the same by actuating a plurality of bolts which engage the inner surface of the cask or barrel to which the bung is applicable.

It also consists of a novel construction of appliances whereby air is readily admitted to the interior of the cask through the bung when desired.

It also consists of a novel construction of expandible ring employed common to the bung and its bushing.

It further consists of novel details of construction, all as will be hereinafter set forth, and specifically pointed out in the claims.

Figure 1 represents a plan view of a bung embodying my invention, showing the bushing and a portion of a cask or a barrel to which the same is applicable. Fig. 2 represents a bottom plan view of the bung seen in Fig. 1. Fig. 3 represents a partial section on line $x-x$, Fig. 2, showing the bung in elevation and the bushing and cask in section. Fig. 4 represents a section through the bung on the line $x-x$, Fig. 2, showing the bung in section and the bushing and cask removed. Fig. 5 represents a portion of the bung seen in Fig. 4, and a sectional view of the device for causing admission of air to the interior of the cask. Fig. 6 represents a sectional view of the interior portion of the bung seen in Fig. 4, showing the air-admitting device in a different position and admitting air to the interior of the cask. Fig. 7 represents a section on line $y-y$, Fig. 3, showing the bolts employed and the means for actuating the same. Fig. 8 represents a sectional view of the outer portion of the bung, showing a special form of expandible ring. Figs. 9 and 10 represent side elevations of the left-hand or inner end of the bung seen in Figs. 3 and

4, showing different forms of bolts which may be employed. Fig. 11 represents a sectional view of the key or wrench employed. Fig. 12 represents a section on line $z-z$, Fig. 11.

Similar letters of reference indicate corresponding parts in the several figures.

Referring to the drawings, A designates a portion of a cask or barrel, and B designates a bushing secured thereto, said bushing having tapering walls C, threaded externally and being provided with the flange D, which engages the outer portion of the cask, the outer portion of the bushing being provided with the annular recess or seat E, the function of which will be hereinafter explained.

F designates the body of the bung; the same having a portion G of reduced diameter, whereby the shoulder H and the flange J are formed, between which is held the ring K, of rubber or other compressible material, said ring having a suitable body and the rounded or beaded portion M, which is seated in said recess E, while that part of the ring underneath the flange J is provided with an annular concavity or recess L, the function of which will be explained.

N designates a plug employed, the same being located within the bushing and having a body portion of substantially uniform diameter which contacts with the annular ribs P and Q of the bung, said plug being provided with a flange R, between which and the rib Q is located the washer or packing S, the inner extremity of the plug N being provided with a pinion T, whose teeth intermesh with the teeth of the racks U, which latter are attached to the bolts V so as to be opposite to each other, said bolts having a recessed portion W and an inclined portion or edge X, the relative location of which will be apparent from Fig. 4, it being evident that any rotation of the pinion T will cause the bolts V to move toward or away from each other, and thus be disengaged from or caused to engage the interior wall of the cask or barrel A, as will be evident from Fig. 3, the movement of said bolts being limited by the stops U², which contact with the rim U³ of the bung or the lugs Z². The bolts V are held in position against the body of the bung,

and their racks are kept in engagement with the pinion T by means of the plate or cap Y, which latter is held in position by the screw Z, which engages the lugs Z². (Seen in Fig. 7.)

5 A' designates a washer or packing which is located within a suitable seat in the cap Y, against which packing the extremity of the plug N contacts. B' designates a cavity in said cap Y, in which is located the disk C', the latter having a washer D' interposed between it and the base of said cavity.

E' designates a cap which engages the walls surrounding the cavity B', said cap being provided with the ports F', which open into the 15 interior of the cask.

G' designates a spring interposed between the disk C' and cap E', said disk C' having the stem H' projecting toward the interior of the cask and through the top of the cap 20 E', while from the opposite side of said disk the stem J' projects, the same passing through the bottom of the cavity B', the washers A' B', and the plug N, said latter stem being provided with a longitudinally-extending recess or vent K', by means of which air can be admitted from the exterior to the cavity B' and thence to the interior of the cask, when the stem J' and disk C' are caused to assume the position seen in Fig. 6.

30 L' designates a cap which is provided with the lips M', which are adapted to engage the under side of the head P² of the plug N, said head having a recessed portion N² thereunder, as will be evident from Fig. 4, and 35 being provided with the oppositely-located recesses Q², the location of which will be apparent from Figs. 1 and 4.

Q' designates a threaded stem which passes through the cap or head L' and is provided 40 with the head R', by means of which said screw can be readily manipulated so that the stem Q' can engage and depress the stem J', whereupon the parts will assume the position seen in Figs. 5 and 6.

45 S' and T' designate different forms which may be given to bolts V, as will be understood from Figs. 9 and 10, the bolt S' being provided with an offset S², while the bolt T' is provided with a greater bevel or inclination 50 than any of the others in order to enable the same to readily engage the interior wall or surface of the cask in which the bung is located.

V' designates a wrench or key by means of which the plug N is rotated, said key having 55 a body portion V' and the handle V² and being provided with a cavity U' in its end, the inner wall of which has on its inner face the lugs X' and the raised portions Y' and the adjacent recessed portions Y² underneath the 60 same, which are adapted to coact with the head P², so that upon placing the key upon the head P² and giving the same a partial rotation the head and key will be interlocked, so that the plug N may be rotated in either 65 direction.

The operation is as follows: The bung hav-

ing been placed in position in its bushing, the bolts V being in the position indicated in Fig. 4, it will be seen that if the plug N be turned in the proper direction the engagement of the 70 pinion T with the contiguous racks will cause the bolts V to move outwardly into the position seen in Fig. 3, said bolts by their contact with the inner surface of the cask thereby pulling the ring K inwardly against the tapering walls of the bushing and simultaneously compressing said ring and causing the outer portion thereof to seat in the annular concavity or seat E of the bushing, said outer portion of said ring being held in position by 80 means of the flange J, and the parts now assuming the position seen in Fig. 3. When it is desired to remove the bung, the plug N is rotated in the opposite direction, thus causing the bolts V to assume the position seen 85 in Fig. 4, whereupon by reason of the resiliency of the ring K the latter will assume the shape seen in Figs. 4, 5, and 8 again. The bolts S' or T' may be used in place of the bolts V, according to requirements, the operation 90 of the bung in other respects being the same. When the parts are in the position seen in Fig. 4, the pressure of the spring G' against the disk C will hold the latter in the position seen, and when for any reason it is desired 95 to equalize the pressure within the cask with the exterior air it is only necessary to place the head L' in the position seen in Fig. 5 and screw the stem Q' into contact with the stem J', whereupon the latter and the disk C' will 100 appear as seen in Fig. 6, and air can readily escape into the interior of the cask, as is evident.

It will of course be understood that the vent K' may be dispensed with, if desired, in which 105 case the cap E' and the cavity B' can also be dispensed with.

It will further be apparent that the ring seen in Fig. 8 is especially applicable to the bushing seen in Fig. 3, since the rounded or 110 beaded portion M seats in the annular recess E, while the rings seen in Figs. 4 and 5 are applicable to any bushing, the rings in each instance being substantially the same with the exception of the beaded portion of the 115 bung, being identical in each instance.

It will further be understood that changes may be made by those skilled in the art which will come within the scope of my invention, and I do not, therefore, desire to be limited 120 in every instance to the exact construction shown and described.

Having thus described my invention, what I claim as new, and desire to secure by Letters Patent, is—

1. A bushing having a recess in its outer face, a bung having a flange and shoulder, an expansible ring on said bung between said flange and shoulder, a rotatable plug in said bung having a pinion on its inner end and 130 sliding bolts having suitable guides and provided with racks engaged by said pinion.

2. In a bung a body portion, an expansible ring encircling the latter, said ring having an annular recess therein, and means for expanding said ring in combination with a bushing having tapering walls and an annular recess near the outer portion thereof in which said ring is adapted to seat. 5
3. A bushing having a hollow bung provided with peripheral flange and shoulder, and interior ribs, an expansible ring between said flange and shoulder, a rotatable plug having a bearing on said ribs and provided with a flange in contact with the inner wall of said bung, a pinion on said plug, bolts adapted to engage the inner wall of a cask in which said bushing and bung are located and means connecting said bolts and pinions. 5
4. In a bung, a body, an elastic ring surrounding the latter, said ring having a recess therein, adapted to be engaged by a suitable portion of said body, a plug rotatably mounted in said bung, gear-teeth on said plug, racks in engagement with said teeth, bolts attached to said racks, and stops for the latter, said bolts being beveled so as to engage the cask in which said bung is located. 5
5. In a bung, an expansible ring suitably supported, means for expanding and contracting said ring, a cavity located in the inner end of said bung, an apertured cap inclosing the same, a disk and a washer seated in said cavity, a spring intermediate said cap and disk, and a longitudinally-recessed stem extending through said bung and having an end attached to said disk, whereby air can be admitted through said bung. 5
6. A bung, a rotatable plug guided therein, sliding bolts adapted to engage the inner wall of a cask in which said bung is held, mechanism connected with said plug for operating said bolts, a plate secured to said plug for holding said bolts in position, and provided with a cavity in its outer end, a cap inclosing said cavity, a movable disk in said cavity having a hollow stem passing through the base thereof and through said plug and having ports adapted to communicate with the interior of the cask. 5
7. A bung, a rotatable plug in said bung, bolts adapted to engage the inner wall of a cask, in which said bung is held and operated by mechanism connected with said plug, a plate holding said bolts in place and having a cavity in its outer end, a cap inclosing said cavity, a disk in said cavity having a hollow stem on one side passing through said plug and a stem on its opposite side passing through the latter-mentioned cap, a spring in said cavity, bearing against said latter cap and said disk, said hollow stem and cavity forming an air-passage through said plug. 5
8. A bushing having a groove in its outer face, a bung with a flange and a shoulder on its periphery, a ring on said bung having a head in said groove, a hollow rotatable plug guided in said bung, sliding bolts adapted to engage the inner wall of a cask in which bushing is held, mechanism connected with said plug for operating said bolts, a cap secured to said bung for holding said bolts in position, 70 a spring-controlled disk guided in a cavity in said cap and provided with a hollow stem passing through said plug and mechanism for operating said stem and disk. 70
9. In a bung, a hollow plug, a plate secured to a suitable portion of said bung, and having a cavity therein, a disk guided in said cavity, and provided with a recessed stem passing through said plug, a cap adapted to engage a recess in one end of said plug, and a threaded stem passing through said cap and engaging said hollow stem. 75
10. In a bung, a hollow plug, a plate secured to one end of said bung and having a cavity in one face thereof, a disk located in said cavity, a recessed stem connected with one side of said disk and passing through said plug, a cap seated in a recess in the other end of said plug, and a threaded stem passing through said cap and adapted to engage said recessed stem, the walls of said plug and latter-mentioned cap having communicating recesses. 85
11. In a bung, a hollow plug, a plate secured to one end of said bung and having a cavity in one face thereof, a disk located in said cavity, a washer intermediate said disk and plate, an apertured cap inclosing said cavity, a spring intermediate said cap and disk, and a longitudinally-recessed stem extending through said plug, and secured to said disk 95 for the purpose of admitting air through the bung. 100
12. In a bung, a body portion, an expansible ring engaging the latter, a recess in the outer portion of said ring, and means for expanding the latter in combination with a bushing having a recess or seat located near the outer periphery thereof, said seat being adapted to be engaged by said ring when expanded. 105
13. In a bung, a body portion, an expansible ring encircling the latter, and having a recess therein, in combination with a bushing having a recess in a suitable portion thereof, in which said ring is adapted to seat, sliding 115 bolts adapted to engage the cask in which said bushing is located, and means for operating said bolts. 110
14. In a bung, a body portion, an expansible ring engaging the latter, said ring having an annular recess in the outer portion thereof, means for expanding said ring, and a bushing provided with an annular recess located near its outer periphery in which a portion of said ring is seated when expanded, in combination with means for admitting air to the interior of the cask in which said bung is located. 120
15. A bushing provided with an annular seat located near the outer portion thereof, a 130 bung supporting an expansible ring the latter having an annular recess in the outer face

thereof, and means for expanding said ring so that a portion thereof will engage said seat when expanded.

16. A bushing provided with an annular seat located near the outer portion thereof, a bung supporting an expansible ring, the latter having an annular recess in its outer portion, means for expanding said ring so that

a portion thereof will engage said seat when expanded, and means for admitting air to through said bung when desired.

JOSEPH P. BAUMGARTNER.
